[57] CLAIM

The ornamental design for a metatarsal forefoot support, as shown and described.

DESCRIPTION

FIG. 1 is a top perspective view of a metatarsal forefoot support showing my new design for use with a left foot; FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof;

FIG. 9 is a top plan view of a metatarsal forefoot support showing my new design for use with a right foot, the other views all being mirror images of those of the first embodiment; and,

FIG. 10 is a top perspective view of the metatarsal forefoot support for use with a left foot in a woman's high heel shoe. The broken line showing of a woman's high heel shoe in FIG. 10 is for illustrative purposes only and forms no part of the claimed design.
